UNITED STATES PATENT OFFICE.

WALTER HERBERT WILKINSON, OF GREENSBOROUGH, AND GEORGE JOSEPH MILNE,
OF ASCOT VALE, VICTORIA, AUSTRALIA.

FOLDABLE BOX AND CASE.

Application filed August 22, 1923. Serial No. 658,798.

To all whom it may concern:

Be it known that we, WALTER HERBERT WILKINSON, a British subject, residing at Southwaite Park, Greensborough, in the 5 State of Victoria and Commonwealth of Australia, and GEORGE JOSEPH MILNE, a British subject, residing at No. 82 Walter Street, Ascot Vale, in the said State, have invented new and useful Improvements in 10 Foldable Boxes and Cases, of which the following is a specification.

This invention relates to that type of box or case which, when empty, is capable, after its top and sides have been removed, of having its ends folded so as to lie parallel with and above the bottom of the box or case, a sufficient space being left between said ends and bottom, to permit of the said top and sides being inserted in said space between 15 the said ends and bottom, the parts being held securely together by the same means which hold the parts together when assembled to form a box or case, thus ensuring a considerable saving in freight as between 20 the manufacturer of the box and his customers, and also in the case of returned empties.

According to our invention, a box or case of the type specified, is so constructed as 30 that, when the parts thereof are assembled, the lower edge of each side rests on the bottom of the box, whilst the ends of the box, which are of less width than the bottom and are pivoted thereto, are situated between the 35 outer extremities of the sides. The top edge of each end of the box projects upwardly slightly above the sides thereof, each end having two parallel horizontal cleats on its outer side, the lower edge of each of the 40 lower cleats extending below the bottom of the end to which it is attached and being in contact with the adjacent end of the bottom and the respective ends of the sides of the box. The top of the box rests on the upper 45 edge of each side and between the upwardly projecting portion at each end. Our invention also comprises the means we have devised for locking the various parts together when assembled to form a box, such means 50 being also adapted to lock the various parts together when the box has been folded up.

Referring to the drawings hereto annexed:—

Figure 1 is a side elevation of a box constructed according to our invention, the top

of the box being shown in its locked position;

Figure 2 is a side elevation of a box constructed according to our invention, the top lock being in its open position and the top 60 removed;

Figure 3 is a plan view of Figure 1;

Figure 4 is an end elevation of Figure 1;

Figure 5 is a plan view of the bottom of 65 the box;

Figure 6 is a side elevation of the bottom and ends of the box (after the sides and top have been removed), one of the latter being in its folded position, namely, parallel with the bottom;

Figure 7 is a side elevation of the box folded up;

Figure 8 is an end elevation of Figure 7.

1 are the sides of the box and 2 the bottom thereof, on which the lower edge of each 75 side rests. 3 are the ends of the box which project, as indicated at 3^A slightly above the sides 1. These ends fit between the sides 1, the lower edge of each end resting upon the bottom 2. 4 is the top of the box. 5 and 5^A 80 are horizontal cleats on the outside of each end 3, and 6 are slots which extend horizontally from end to end of said cleats 5 and 5^A. The lower cleats 5^A, as shown in Figures 1 and 2, project below the bottom edge of 85 the sides 1 of the box. Each end of the bottom 2 of the box abuts against the projecting ends of the cleats 5^A. 7 are cleats, one at either end, and on the lower side of said bottom 2. 8 are slats which extend horizontally from end to end of said cleats 7. 10 are cleats one at either end, and on the outside of said top 4. The inner edge of each 90 of these cleats 10 is bevelled as at 11. 12 is a cleat situated midway between said cleats 95 10. The means for holding the parts together when assembled to form a box will now be described. 13 are rods which extend through the slots 6 in the cleats 5 and 5^A. The said rods at their outer ends are bent 100 inwardly at right angles, as at 14, and formed integral with a vertical rod 15, whereby, when the parts of the box are assembled, the said rods 13 are held rigidly in their respective slots 6. 16 are rods which 105 are pivoted in the slots 8 in the cleats 7 on the lower side of the bottom 2. The ends of these rods 16 extend through the said slots 8 and are bent outwardly at an angle, as at 16^A, and terminate in a loop 17, which en-

gages with the right-angled extension of the lower of the rods 13 at the point where such extensions connect with the vertical rods 15. 18 are fastening devices for the top of the box. These devices are pivoted at their ends 19 to the right-angled extension of the upper of the rods 13, at the point where such extensions connect with the vertical rods 15.

To assemble the parts of the box together, 10 the pivoted ends 3 of the box are brought into a vertical position whereby the outer ends of the bottom 2 are in contact with the projecting lower portion of the cleat 5. The sides 1 are then slipped between the 15 outer edges of the said sides and the vertical rods 15, so that the lower edges of said sides rest on the bottom 2 with their outer ends abutting against the outer edges of the ends 3. The top 4 is then placed in position so 20 that it rests upon the upper edges of the sides 1 of the box, whilst its ends abut against the projections 3^A on the ends 3 of the box. The pivoted fastening devices 18 are then forced over the bevelled edge 11 25 of the cleats 10, thereby locking the top in position and assisting in bracing the parts of the box together.

To dismantle the box, the sides 1 are first removed, and then one of the pivoted ends 3 of the box is folded parallel with the bottom 2, as shown in Figure 6. Similar action is then taken as regards the other end. As will be seen from the said figure, a space is left between the ends and the bottom, and, into this space, is packed the sides and top of the box, the means used for holding the various parts together when assembled, also holding the parts together when dismantled.

40 We claim:—

1. In a foldable box or case, the combination with the underside of the bottom of the box having a cleat at each end extending from side to side thereof, each cleat

having a longitudinal slot therein, of sides, 45 the lower edge of each of which rests on said bottom, pivoted ends between said sides, the upper portion of said ends projecting above the sides, horizontal parallel cleats on the outside of each end, each cleat having 50 a longitudinal slot therein, the lowermost cleat extending below the end to which it is attached, and being in contact with the adjacent end of the bottom, and the respective ends of the sides of the box, a top 55 which rests on the upper edge of each side and between the upwardly projecting portion at each end, and means for locking the various parts of the box together when assembled to form a box.

2. In a foldable box or case, as claimed in the preceding claim, means for locking together the various parts when assembled (said means being also adapted to lock said various parts together when folded up), comprising rods which pass through and are rigidly held in slots in cleats on the outside of the ends of the box, the ends of the rods being bent inwardly at right angles and formed integral with a vertical rod, rods 70 which are pivoted in the slots in the cleats beneath the bottom of the box, the ends of said rods being bent outwardly at an angle and each terminating in a loop, each loop engaging with the adjacent right-angled extension of the rod in the lower cleat on the outside of the end of the box, at the point where such extension connects with the vertical rod, and fastening devices for the top, the lower ends of said fastening devices being each pivoted at the point of intersection of the vertical rod with the adjacent right-angled extension of the rod in the upper cleat on the outside of the ends of the box.

WALTER HERBERT WILKINSON,
GEORGE JOSEPH MILNE.
